UNITED STATES PATENT OFFICE.

GEORGE B. DEARDORFF, OF CANAL DOVER, OHIO.

TOOTHPICK.

SPECIFICATION forming part of Letters Patent No. 579,139, dated March 23, 1897.

Application filed November 27, 1896. Serial No. 613,557. (No model.)

To all whom it may concern:

Be it known that I, GEORGE B. DEARDORFF, a citizen of the United States, residing at Canal Dover, in the county of Tuscarawas and State of Ohio, have invented certain new and useful Improvements in Toothpicks; and I do hereby declare that the following is a full, clear, and exact description of the same, reference being had to the annexed drawings, 10 making a part of this specification, and to the letters of reference marked thereon, in which—

Figure 1 is a view of the pick, showing all of its parts properly assembled. Fig. 2 is a 15 detached view of the cap and its cleaning-head. Fig. 3 is a view showing a portion of the pick-handle, showing the cap removed. Fig. 4 is a similar view showing the tip removed. Fig. 5 is a detached view of the tip. 20 The present invention has relation to toothpicks; and it consists in the different parts and combination of parts hereinafter described, and particularly pointed out in the claim.

Similar letters of reference indicate corresponding parts in all the figures of the drawings.

In the accompanying drawings, A represents the handle, which may be constructed in the 30 ordinary manner, reference being had to properly attaching the bristles *a* and the different parts belonging to and forming a part of the pick proper. One end of the handle A may be provided with the ordinary brush, to which the bristles *a* are attached in the ordinary manner, and the opposite end of the handle is provided with the longitudinal recess *b*, which is for the purpose of receiving and holding the tip *c*, which tip is so formed that 35 it will snugly fit the recess *b* when placed in the position illustrated in Fig. 3, and is for the purpose of providing a suitable toothpick.

For the purpose of providing a means for easily removing the tip *c* to insert a new one the 40 lateral opening *d* is provided, which lateral

opening leads into the recess *b* and is so located that any suitable object can be placed back of the tip to press it forward.

For the purpose of protecting the tip *c* and at the same time providing a stiff brush or 50 rubbing-head the cap *B* is provided, which cap is provided with the rubbing-head *C*. The rubbing-head *C* is notched or creased at its outer end, so as to provide a rough rubbing-surface and is preferably formed of rubber; 55 but I do not desire to be confined to any particular material, inasmuch as various kinds of material may be used without departing from the nature of my invention.

In use, when it is desired to use the brush 60 in the ordinary manner, the cap or cover *B* is placed in the position illustrated in Fig. 1, which brings both the brush and rubbing-head into proper position for use, and when it is desired to use the tip for cleaning the 65 cavities of teeth the cover *B* is removed, as illustrated in Fig. 3, at which time the tip *c* is exposed and can be used as a toothpick.

The toothpick here described is more particularly adapted for cleaning false teeth and 70 is especially designed for that purpose; but it will be understood that it may be used without any particular reference to the kind of teeth it is used upon.

Having fully described my invention, what 75 I claim as new, and desire to secure by Letters Patent, is—

As an improved article of manufacture a toothpick consisting of the handle *A*, provided with the recess *b*, having therein the 80 tip *c*, the lateral opening *d*, leading into the recess *b*, substantially as and for the purpose specified.

In testimony that I claim the above I have hereunto subscribed my name in the presence 85 of two witnesses.

GEORGE B. DEARDORFF.
